UNITED STATES PATENT OFFICE.

HERMAN D. SCHROEDER, OF LOS ANGELES, CALIFORNIA.

EXHIBITING DEVICE.

1,120,982.

Specification of Letters Patent. Patented Dec. 15, 1914.

Application filed September 29, 1913. Serial No. 792,312.

To all whom it may concern:

Be it known that I, HERMAN D. SCHROEDER, a citizen of the United States, residing at Los Angeles, in the county of Los Angeles and State of California, have invented a new and useful Exhibiting Device, of which the following is a specification.

This invention relates to a device for exhibiting advertisements, pictures, etc., and 10 the main object of the invention is to provide for a large exhibiting capacity in a comparatively small and compact machine.

A further object of the invention is to provide an exhibiting device in which the time 15 of exhibition of each picture or advertisement may be controlled independently of the speed of operation of the machine.

Other objects of the invention will appear hereinafter.

20 The accompanying drawings illustrate an embodiment of my invention, and referring thereto:

Figure 1 is a front elevation of the exhibiting device. Fig. 2 is a transverse section 25 thereof, on line x^2-x^2 in Fig. 1. Fig. 3 is a transverse section thereof on line x^3-x^3 in Fig. 1. Fig. 4 is a section on line x^4-x^4 in Fig. 3. Fig. 5 is a section on line x^5-x^5 in Fig. 3. Fig. 6 is a section on line x^6-x^6 30 in Fig. 2. Fig. 7 is a rear elevation of the exhibiting device, the inclosing case being shown in section. Fig. 8 is a diagram of the circuit connections. Fig. 9 is a section on line x^9-x^9 in Fig. 7. Fig. 10 is a section on line $x^{10}-x^{10}$ in Fig. 7. Fig. 11 is a section 35 on line $x^{11}-x^{11}$ in Fig. 7. Fig. 12 is a detail elevation of the controlling gear for determining the period of reversal. Fig. 13 is a section on line $x^{13}-x^{13}$ in Fig. 7. Fig. 14 is a section on line $x^{14}-x^{14}$ in Fig. 7. Fig. 15 is a section on line $x^{15}-x^{15}$ in Fig. 14. Fig. 16 is a section on line $x^{16}-x^{16}$ in Fig. 14.

The exhibiting device is inclosed in a case 1 and mounted in a frame 2, which preferably consists of angle bars 3 riveted together to form front and rear rectangular frames which are connected together at top and bottom by plates 5, 6 and 7 riveted to said angle bars. Plates 6 and 7 are secured 45 to a base 8. The exhibiting curtain 9 is mounted on upper and lower curtain rollers 10 and 11, and slides over guide rolls 29 on frame 2, said curtain being removably attached to the rollers by rings 9' in the curtain engaging hooks 10' in the rollers. The inclosing case 1 formed preferably of sheet 50

metal, is adapted to slide vertically over the frame 2 aforesaid, so as to completely inclose the mechanism at top, front, rear and sides. Said inclosing case is formed at its 60 front with an opening provided with a pane 4 of glass or other suitable material, through which a portion of the curtain or exhibiting means 9 is exposed to view. Reflectors 24 are provided at the top and bottom of said 65 opening in the front of the case, and electric lamps 24 are provided within said reflectors, so that the light from said lamps is reflected onto the exhibiting means, reflecting surfaces 24' being also provided, extending obliquely inward from said lamps to throw the light onto the lower and upper portions of the picture, with greater intensity than on the middle portion thereof. Said case is further provided with flanges 30 extending to 70 75ward the exhibiting curtain to aid in guiding the same.

The plates 5 at the top of the frame 1 are formed with bearings for curtain roller 10. A suitable form of bearing is shown in Fig. 80 6, each of the plates 5 being formed of two sheet metal parts 5' riveted together and having opposite openings 12 rabbeted or flanged as shown at 13, to form annular ball races for balls 14 engaging in an annular 85 groove 16 in a hub 17 mounted to rotate with the roller 10. To facilitate assemblage of the parts the roller 10 is made separate from the hubs 17 and is provided in one end with perforations 18 for receiving a pin 19 on a disk 90 20 carried by the corresponding hub 17. The sheet metal parts 5' are assembled with the balls 14 and hub 17 before the said parts 5' are riveted together, and the roller 10 is brought into position between the opposite 95 hubs 17 when the plates are being secured to the machine frame. A shaft 21 extends through the roller 10 and the hubs 17 thereof and carries the box or casing 22 for a spring 23, said spring being secured at one 100 end to said box and at the other end to the hub 17, so as to resiliently connect said shaft 21 and the roller 10.

The lower roller 11 is provided at one end with a stud 25 engaging in a socket 26 in a bearing member 27 rotatably mounted in a ball bearing 28' in a plate 28 constructed similarly to the above described plates 5, but removably secured to the frame of the machine. For this purpose the removable plate 110 28 may be secured to the fixed plate 6 by means of a screw 31 on the plate, extending

through a perforation 32 in the plate 28 and a nut 33 screwing on said screw. Hooks 34 on said plate 6 extend through notches 35 in said plate 28 and engage over said plate to hold same in position at its top. At its other end the roller 11 is provided with a hole 37 for receiving a bearing pin 38 rotatably mounted in a ball bearing 39 in frame plate 7 and in a ball bearing 40 in a frame plate 41 mounted on the base 8 of the machine. A disk 44 on said bearing member 38 is provided with a pin 45 engaging in a recess 46 in the end of roller 11, so as to cause said roller to turn with said bearing member. By means of this construction the lower roller is rendered readily removable, it being only necessary to unscrew the nut 33, remove the plate 28 and then withdraw the roller endwise from the bearing member 38.

The two rollers 10 and 11 are operated simultaneously from an operating shaft 48 mounted in bearings 49 on a frame plate 50 secured to vertical bars 51 on the rear frame member aforesaid, said shaft 48 carrying two sprocket wheels 54 and 55 connected respectively by sprocket chains 56 and 57 to sprocket wheels 58 and 59 on the respective upper and lower rollers. Wheel 55 also operates as a cam wheel, as hereinafter set forth.

Operating shaft 48 is driven from a motor 60 by any suitable connection, for example, by a screw 61 operated by the motor and engaging a worm gear 62 on a shaft 63 mounted to rotate on the machine frame and carrying a screw 64 engaging a worm wheel 65 on said shaft 48. A clutch is provided between the shaft 69 of the motor 60 and the operating screw 61 aforesaid, said clutch comprising disks or cones 68, 68', secured to the respective members 69 and 61, clutch member 68' being splined to the motor shaft so as to turn therewith, and being provided with an annular neck 70 engaged by a controlling lever 71, and with a spring 72 tending to close said clutch.

In order to provide for compactness of the device, together with capacity for exhibiting large pictures or signs, I provide means whereby the curtain rollers 10 and 11 may be given a plurality of rotations at each exhibiting operation, thereby enabling small rollers to be used. For this purpose controlling devices are provided for the motor 60, comprising a switch 73 and a controller for said switch 73 operated, for example, at every alternate rotation of the shaft 48. Switch 73 comprises a lever 74 of insulating material pivotally mounted at 75 and carrying contact means adapted to control the circuit of the motor as hereinafter set forth, one arm 78 of this lever being connected by a spring 79 to a reversing fulcrum member or arm 80, which controls the

pressure on said spring 79 so as to tend to throw the switch lever 74 in one direction or the other, from a central position. A link 81 is connected to said switch lever and to one arm of a bell crank 82, whose other arm is connected by a spring 83 to a link 84 pivoted to an operating lever 85 which is pivotally mounted on the frame plate 50. Link 84 is provided with an elongated slot 87 which engages a pin 88 on the bell crank 82 aforesaid, so as to support said link. The link 81 forms with the switch lever 74, a toggle, and a pin 76 is provided at the knuckle of this toggle, to engage detent means as hereinafter set forth.

A rod 90 pivotally connected to one end of lever 85 slides in a bracket 89' on a bar 89 which is slidably mounted in a guide block 91 and carries a roller 92 adapted to engage in a semi-circular notch 93 in a flange 94 on the wheel 55 on the shaft 48. A spring 86 is interposed between members 89 and 90 tending to spread them apart. A cam projection 95 on said wheel 55 engages a roller 96 on a slide 97 which is slidably mounted in a guide block 98. A member 110 is slidably mounted in said slide 97, and carries a roller 99 engaging an inclined face 100 on a member 101 suspended from and pivoted at 102 to a rocking lever 103. A spring 111 engages said members 97 and 110, to spread the same apart. A spring catch 114 on block 98 is adapted to engage a pin 119 on member 110 to lock the same, and said spring catch and the slide 97 are provided with inclined lugs 114' and 97' to release the spring catch on movement of the slide. Said rocking lever 103 is weighted as at 104 so as to tend to raise member 101 and to the weighted end of the lever is pivotally connected a rod 105 which is pivoted at its lower end to a head 106. Said head 106 is split and embraces a sleeve 107 which extends through the upper head 108 of a dash pot cylinder 109, and is provided at its lower end with a piston 112, perforated at 113, and with a shoulder 107' on which rests a floating disk 115, which when the piston is descending, closes the perforations 113. Said sleeve is perforated laterally as shown at 116 and the head 106 is provided with a downwardly extending rod 117 which serves to close said perforations 116 more or less to provide for regulation of the rapidity of action of the dash pot. The sleeve 107 is adjusted relatively to the rod 117 by loosening a clamp screw 118 which binds the split head 106 on said sleeve, sliding the sleeve within the head and then tightening the screw 118.

The member 101 above referred to operates between the roller 99 and controlling lever 85, and acts as a spacer or intermediate block for determining the operation of said controlling lever by the slide member 130

or bar 97. The link 84 connected to lever 85 is provided with an upwardly extending spring catch 120 having an inturned ledge or shoulder 121 adapted to engage a pin or projection 122 on the lever 103 aforesaid, so as to lock the member 101 in lowered position. Lever 103 is operated in opposition to its restoring weight 104 by an operating rod 124 slidably mounted in an opening 125 in a bracket 126 on a lever 103 and pivotally connected at its lower end at 127 to a gear wheel 128 whose shaft 129 is mounted in a fixed bearing 130 on the frame 50. A spring 132 is provided between the bracket 126 aforesaid and a collar 133 which is adjustably fastened on the rod 124 by a screw 134. The gear wheel 128 on shaft 129 engages a gear wheel 137 on the operating shaft 48 aforesaid, said gear wheel 137 being proportioned relatively to gear wheel 128 so as to drive the shaft 129 at one-half the rotative speed of the shaft 48, so that an upward movement of the lever 103 and a downward movement of the member 101 is secured at each alternate rotation of the cam wheel 55. Wheel 137 is connected to shaft 48 by a lost motion connection, said wheel having a notch 137' in its hub in which engages a member 48' on shaft 48, so that shaft 48, when it reverses its motion will turn through a certain angle before it picks up and carries around the wheel 137. Shaft 129 also carries a screw 140 engaging a worm wheel 141 rotatably on a stud shaft 142 on a bracket 143 extending over the shaft 48. Worm wheel 141 is provided with an annular series of perforations 144, see Fig. 12, adapted to receive two pins 145 and 146, the position of these pins in the series of perforations determining the number of pictures or signs that will be exhibited. A retaining plate 147 extends over the worm wheel 141 so as to retain the said pins in position, said disk being held in position by the screw 148. A reversing member 150 is slidably mounted on a pin 151 on the frame 50, said member 150 having a slot 152 slidably engaging said pin, one end of said member 150 having a lateral projection 153 extending into the path of movement of the pins 145 and 146 aforesaid, so as to cause the said member 150 to be moved in one direction or the other by engagement of said pins with said projections, and the other end of said member 150 being pivoted at 154 to the reversing lever 80 aforesaid for the electric switch.

Means are provided for locking the electric switch in open position while the picture is being exhibited, said means consisting of a pair of detents or hooks 160 for engaging the pin 76 on toggle 74, 81, said hooks being formed on a bar 161 mounted to slide vertically on pins 162 on frame 50, said bar having vertical slots 163 slidably

engaging said pins. A spring 165 is connected to one of said pins and engages a flange or projection 166 on the bar 61 so as to tend to raise said bar. The lever 103 is provided with a projection or shoulder 167 adapted to engage said projection 166, so as to depress the detent devices 160 aforesaid. 70

The switch 73 is preferably constructed as shown in Figs. 14 to 16 and comprises rear and front plates 170 and 171 of insulating material, and spacer plates 172 also of insulating material, forming a segmental chamber 173 in which the switch lever 74 works, the pivot 75 for said switch lever being at the apex of the segment. Metal 75 strips 175, 176, 177 and 178 are mounted in said insulating plate 171 and metal strips 175', 176', 177' and 178' on plate 170, said members 175, 175', being exposed on the inside of the plate 170 and 171 at the mid width thereof and members 176, 176', 177, 177', 178 and 178' being exposed at the inside faces of the plates 170 and 171 only at each side of the mid width. In the case of the front plate, these strips extend concentrically with the pivotal center of the switch and the same is true for the strips 175' and 176' on the rear plate, but the strips 177' and 178' on the rear plate cross one another as shown in Fig. 15, so as to provide 85 for reversal. The switch lever 73 is provided with contact pins or members 180, 181, 182 and 183 extending through perforations in said switch lever and pressed apart by springs 184 so as to cause them to 90 engage with the contact members 175, etc. 95

The circuit connections are as follows: The wires 190, 191, of any suitable supply circuit are connected to contact springs 192, 193, mounted on an insulating block 194 on 100 the inclosing case 1, an extra contact spring 195 being provided on block 194 for the purpose hereinafter set forth. Contact springs 196, 197 and 198 are mounted on an insulating block 199 on the machine frame 110 2 and adapted to engage respectively with the contacts 192, 193 and 195 when the case is slipped over the machine frame as shown in Fig. 7. A wire 200 leads from contact 196 to contacts 175, 176, of switch 73. Wire 115 201 leads from contact 175' of switch 73 to the lamp or lamps 24 and thence to contact 198. Contact 195 which engages contact 198 is connected to contact 193 and circuit wire 191. Contact 176' of switch 73 is connected 120 by wire 203 to one coil 204 of the motor field magnet, a wire 205 leading from said coil to contact 177 of the switch, contact 177 of the switch being connected by wire 209 to the armature 206 of the motor from 125 which a wire 207 leads to contact 178 of the switch, contact 178' of the switch being connected by wire 211 to the other motor field coil 204' from which a wire 210 leads to contact spring 197. 130

The operation is as follows: The curtain 9 is affixed to rollers 10 and 11, for example, by a detachable connection such as above described, and the pins 145 and 146 are placed on the wheel 141 so that the number of perforations between said pins corresponds to the number of pictures or signs carried by the curtain. Assuming that the parts are in the position shown in Fig. 7, 5 the motor circuit is closed as follows: from line wire 190 through contacts 192, 196, wire 200, switch contact 176, switch pin 181, contact 176' wire 203, motor field coil 204, wire 205, switch contacts 177 and 178, wire 207, armature 206, wire 209, switch contacts 177, 10 178', wire 211, motor field coil 204', wire 210 and contacts 197 and 193 to line wire 191. Current passing in this circuit energizes the motor as a series motor 15 and causes the shaft 63 thereof to rotate. Assuming that at this time the roller 92 is running on the un-notched part of the flange 94 of the cam wheel 55, the clutch member 68' is held in engagement 20 with clutch member 68, so that the screw 61 is rotated by the motor, thereby rotating shafts 63 and 48. Through the gears 137, 128, shaft 129 is also rotated, causing the rod 124 to be raised, bringing the spring 25 132 thereon against the bracket 126 on lever 103 and raising the counter-weighted end of said lever and the dash pot piston connected thereto. This upward movement of the dash 30 pot piston is unrestrained, the disk 115 resting on the shoulder 107 and falling away from the perforations 113 in the piston 112, so that liquid may pass readily from the space below the piston through the perforations 113 to the space above the piston. 35 This movement of the controlling lever 103 also allows the detent member 161 to rise and causes the member 101 to descend, bringing the lower part of said member 101 between the roller 94 and the lever 85. As 40 the member 101 descends in this manner the projection 122 on the adjacent end of lever 103 snaps under shoulder 121 of spring catch 120 and locks member 101 down, thereby locking the controlling lever 103 in 45 position with its weighted end raised. At this time the cam 95 has passed the roller 96 in its first turn, and the inclined face on the member 101 presses the roller 99, carrier 110, slide 97 and roller 95 back until roller 50 95 presses on the flat part of cam wheel 55, and then compresses the spring 111 until the pin 119 on carrier 110 snaps under spring catch 114, thereby locking the roller 99 in retracted position. In the second rotation of the cam wheel 55, the cam member 55 95 thereon comes into engagement with the roller 96 on the slide 97, compressing spring 111 until the inclined faces 114', 97' on members 114 and 97 engage to lift the spring catch 114 from the pin 119 and free the

carrier 110 from roller 99, whereupon roller 99 engages member 101 and throws lever 85 back, resulting in endwise movement of link 84, so as to slide the spring catch 120 from beneath the projection 122 on lever 103 and free said lever. This endwise movement of link 84 also brings pressure through spring 83 on the bell crank 82 in such manner as to quickly raise the arm of said bell crank connected to link 81, and jerk or snap the toggle, composed of link 81 and lever 74 toward dead center position, the pin 76 at the knuckle of the toggle snapping over one of the hooks 160 and said hook arresting the return movement of the toggle, 80 which tends to result from the action of the spring 79 in position of the reversing means shown in the drawing. The described operation of lever 85 by cam 95 causes spring 86 to be compressed, and as soon as notch 93 in flange 94 becomes beneath roller 92 said roller snaps into said notch and allows clutch 71 to be operated by spring 86 so as to open the clutch and release the notch from the transmission gearing, spring 92 85 when compressed as above stated being stronger than the clutch closing spring 72. The movement of the switch lever 74 toward central position as above described, 90 opens the motor circuit at contacts 176, etc., 95 and closes the lamp circuit as follows: from line wire 190 through contacts 192, 196, wire 200, contacts 175, 180, 175', wire 201 through the lamp or lamps 24 and contacts 198 and 195, to wire 191. The above described operation, therefore brings the curtain winding mechanism to rest and is so timed that a sign or picture will then be exhibited through the opening in the case and the picture so exhibited is illuminated by the 100 lamp or lamps 24.

The moment that the controlling lever is released as above described by sliding the spring catch 120 from over detent 122, it begins to descend under the action of weight 104, this descent being resisted and retarded by the action of the dash pot, the disk 115 at this time coming against the piston 112 and closing the perforations 113 so that the liquid can only pass through the bore of 110 sleeve 107 and through the perforations 116 in said sleeve, said perforations being relatively small and being closed to any desired extent by the rod 117, so as to retard the passage of liquid therethrough. By this means the time of descent of the dash pot piston may be controlled independently of the speed of operation of the motive devices and the time of exhibition of each picture correspondingly controlled. As the dash 120 pot piston descends in this manner, the controlling lever 103 eventually reaches a position in which the projection 167 thereof strikes projection 166 on the detent bar 161, thereby removing the hook 160 aforesaid 125 130

- from the pin 76 and allowing the switch lever 74 to be thrown back to closed position shown in Fig. 7, by the action of springs 79 and 90, it being understood that in this movement of the controlling lever 5 103, the member 101 is raised so that its lower portion is withdrawn from between the roller 99 and the lever 85, leaving the levers 85 and 82 free to be operated by 10 springs 79 and 90 to open the switch. The movement of lever 85 in the closing of the switch releases the tension of spring 90 on clutch lever 71 and allows clutch spring 72 to close the clutch, putting the motor in 15 operative connection with the transmission gearing, and at the same time the spring 72 operates lever 71 to move roller 92 out of notch 93 in flange 94 of cam wheel 55, so that the said wheel and connected parts 20 start another rotation.
- The operation of shaft 48 as above described causes the rollers 10 and 11 to turn, so as to wind the curtain 9 off of one of said rollers and on to the other, the spring 23 25 for roller 10 allowing a certain amount of differential movement required by the variation in effective diameters of the rollers as the curtain winds off or on the rollers.
- In each double rotation of shaft 48, as 30 above described, the screw 140 is turned one revolution and advances the worm gear 141 a distance corresponding to one of the holes 144. This operation is repeated for each picture or sign on the curtain until the last one is reached. Pin 145 on wheel 141 then strikes reversing member 150 and shifts the fulcrum member 80 so as to move the fulcrum of spring 79 to the other side of the dead center with respect to the pivot of 35 switch lever 74. In the next insuing operation of the toggle 81, 74 by the bell crank 82, the action of spring 79 urges the toggle past the dead center position and causes it to come to rest with pin 76 in engagement 40 with the other hook 160. This causes the motor circuit to be closed in a reverse direction with respect to the armature circuit, the contacts 177 and 178 being reversed at this side, so that the motor runs in the reverse direction, and the curtain is therefore wound in the reverse direction, the operation proceeding in other respects as above 45 described. In this reversing operation the lost motion connection 48', 137' above described, causes the wheel 128 for operating rod 124 to be operated only in the second rotation of the cam wheel 55 and thus insures that the full movement of the curtain will be provided for. This is necessary for 50 the reason that the controlling means 95, 97 above described requires a certain leeway of movement relative to the reversible devices in order to insure a full movement of the curtain in either direction.
- 60 One advantage of the present invention is that is enables the current to be applied to the motor, intermittently, the motor being out of circuit while the curtain is arrested, and the period of such arrest being determined by means independent of the motor, 70 namely, the dash pot. By this means I am enabled to use a motor such as a "universal" motor, adapted for either alternating or direct current work, but not capable of receiving alternating current for more than 75 a short time, on account of the heating. Moreover, by this construction the period of exhibition of each picture or sign may be adjusted, by adjustment of the dash pot piston, independently of the speed of the 80 motor.
- Another advantage of the exhibiting device above described is that it takes up no more room than is required for the curtain and the winding rollers, the operating mechanism being located wholly within the space between the rollers and behind the curtain. The device is intended particularly for large pictures and signs and by reducing the rollers to the smallest possible size and having 85 the operating mechanism between the rollers, the structure occupies little more space than would be required by a frame for the picture or sign.
- By unwinding the curtain from the upper roller, releasing it from said upper roller by removing ring 9' from hook 10' and then removing plate 28, the roller may be withdrawn from the machine, with the curtain wound thereon, and another roller with a 90 different curtain substituted.
- It will be noted that the lamps are switched in when the motor is turned off, and vice versa. The light is thrown by lamps 24 and reflectors 24' and 24" obliquely down and back against the picture or sign so as to more strongly illuminate the upper and lower portions thereof. This is particularly desirable in exhibiting pictures, since it gives a strong illumination of the foreground 105 and background as compared with the middle distance, making the foreground prominent and giving the effect of sky illumination at the background, and giving depth to 110 the picture.
- What I claim is:
1. An exhibiting device comprising a curtain, rollers on which the curtain is wound, an electric motor, a mechanical connection for operating said rollers from said motor, a reversing switch for said motor, operating means for said switch connected to be operated by said motor, to open said switch at definite positions in the travel of said curtain, means tending to move said switch to closed position, means for retaining said switch in open position, a controlling means for said switch retaining means, tending to move to position to release said switch, means operated by the motor for moving 115

said controlling means away from such position, means for retarding and timing the switch releasing movement of said controlling means, reversing means for changing 5 the operation of said operating means on said switch, to move the switch to reversed position, and mechanism operated by the mechanical connection between said rollers and said motor to operate said reversing 10 means after a predetermined number of operations of said switch.

2. An exhibiting device comprising a curtain, rollers on which the curtain is wound, an electric motor, gearing connecting said 15 motor to said rollers, a cam operated by the aforesaid gearing, a switch for said motor, switch operating means operated by said cam for moving the switch to open position, means for retaining the switch in open position, 20 a controlling means tending to move to position to release said switch retaining means, means for operating said controlling means away from such releasing position by said motor, means for locking said controlling means in operated position, said locking means being adapted to be released by 25 operation of said switch operating means, and means for retarding and timing the return movement of said controlling means, to determine the period of arrest of said motor.

3. An exhibiting device comprising a curtain, rollers on which said curtain is wound, an electric motor, mechanical connections 35 including a clutch for operating said rollers by said motor, a reversing switch for said motor, reversing means, and a spring connected thereto and operating on said switch to tend to move the switch to closed position in either direction, according to the 40 position of the reversed means, operating means for opening said switch, a cam operated by said mechanical connections for operating said operating means, clutch opening 45 means operated by said operating means, a rotary member connected to said mechanical connections, and stop means engaging with said rotary member to arrest the curtain in definite position, said stop means 50 being connected to said clutch to time the opening thereof by said clutch opening means, simultaneously with the arrest of the curtain, and means controlled by the 55 operation of an electric motor for operating said reversing switch after a predetermined number of operations of the motor.

4. An exhibiting device comprising a curtain, rollers on which the curtain is wound, an electric motor, gearing connecting said 60 motor to said rollers, a cam operated by the aforesaid gearing, a switch for said motor, switch operating means operated by said cam for moving the switch to open position, stop means for said gearing, connected to 65 said switch operated means to stop the gear-

ing simultaneously with the opening of the switch, means for retaining the switch in open position, a controlling means tending to move to position to release said switch retaining means, means for operating said controlling means away from such releasing position by said motor, means for locking said controlling means in operated position, said locking means being adapted to be released by operation of said switch operating means, and means for retarding and timing the return movement of said controlling means, to determine the period of arrest of said motor.

5. An exhibiting device comprising a curtain, rollers on which said curtain is wound, an electric motor, mechanical connections for operating said curtain in either direction by said motor, a reversing switch for said motor, a reversing device, a spring connected thereto and operating on said switch to tend to move said switch to closed position in either direction according to the position of the said reversing device, means operated by said motor to open said switch, means for retaining said switch in open position, dashpot controlled means for releasing said retaining means, means for moving the dashpot controlled means away from releasing position upon opening of the 95 switch, and means operated by said electric motor for operating said reversing device after a predetermined number of operations of said switch.

6. In an exhibiting device, a curtain winding mechanism, a motor therefor, a switch for said motor comprising a lever and a link connected to said lever to form a toggle, and an operating member connected to said link for operating said switch by straightening said toggle, said operating member being connected for operation by said motor.

7. In an exhibiting device, a curtain winding mechanism, a motor therefor, a switch for said motor comprising a lever and a link connected to said lever to form a toggle, an operating member connected to said link for operating said switch by straightening said toggle, said operating member being connected for operation by said motor, and spring means operating on said switch lever tending to move the toggle from straight position.

8. In an exhibiting device, a curtain winding mechanism, a motor therefor, a switch for said motor comprising a lever and a link connected to said lever to form a toggle, an operating member connected to said link for operating said switch by straightening said toggle, said operating member being connected for operation by said motor, spring means operating on said switch lever tending to move the toggle from straight position, and a movable support for 130

said spring means for reversing the throw of the switch from central position.

9. In an exhibiting device, a curtain winding mechanism, a motor therefor, a switch for said motor comprising a lever and a link connected to said lever to form a toggle, an operating member connected to said link for operating said switch by straightening said toggle, said operating member being connected for operation by said motor, spring means operating on said switch lever tending to move the toggle

from straight position, a movable support for said spring means for reversing the throw of the switch from central position, 15 and means operated by said motor for shifting said movable spring support.

In testimony whereof, I have hereunto set my hand at Los Angeles, California, this 22nd day of September, 1913.

HERMAN D. SCHROEDER.

In presence of—

A. P. KNIGHT,
LORRAINE E. DURROW.
